UNITED STATES PATENT OFFICE.

AGNES HAVILAND AND ELINOR D. PRATT, OF SAN FRANCISCO,
CALIFORNIA.

DESIGN FOR A DOUCHE-PAN.

SPECIFICATION forming part of Design No. 27,024, dated May 4, 1897.

Application filed March 13, 1897. Serial No. 627,429. Term of patent 14 years.

To all whom it may concern:

Be it known that we, AGNES HAVILAND and ELINOR D. PRATT, citizens of the United States, residing at San Francisco, in the county of San Francisco, State of California, have invented and produced a new and original Design for Douche-Pans, of which the following is a specification, reference being had therein to the accompanying drawings.

- 10 Figure 1 is a perspective view of a douche-pan showing our design. Fig. 2 is a substantially central vertical longitudinal section through the same. Fig. 3 is a vertical trans-
verse section.
- 15 The leading feature of the design consists in the outline of the pan, being flat upon the under side, its surrounding wall being higher at the back than at the front, and a surround-
ing lip or flange upon the inner upper face
20 of the pan, this flange or lip being widest at the rear and sloping toward the front, while the remaining portion thereof inclines slightly toward the center of the pan, the line of junc-

ture of this flange or lip and the vertical wall being upon a curve. 25

A is the bottom of the pan, which is flat. B is the vertical surrounding wall. It is of considerably less height at the front C than at the rear D, and at its upper edge is provided with the inwardly-extending flange or 30 lip E, which is narrow at the front, but wider at the rear, which latter portion slopes toward the center of the pan, as shown. This leaves a substantially heart-shaped opening in the top. In the flange or lip at the front is an 35 opening F.

What we claim as new is—

The design for a douche-pan, substantially as herein shown and described.

In testimony whereof we affix our signatures in presence of two witnesses. 40

AGNES HAVILAND.
ELINOR D. PRATT.
